INSULATOR

Robert H. Walker, Barberton, Ohio, assignor to
The Ohio Brass Company, Mansfield, Ohio, a
corporation of New Jersey

Application April 24, 1935, Serial No. 17,981

1 Claim. (Cl. 173—318)

This invention relates to electric insulators and especially to insulators for use in regions where the atmosphere is apt to be contaminated with fog, dust, smoke or other foreign matter which 5 is apt to collect upon the surface of the insulator and diminish its efficiency.

One object of the invention is to provide an insulator having a relatively short section length and having long flashover and leakage paths, 10 considerable portions of which are protected from contamination.

A further object of the invention is to provide an insulator having a minimum exposure of metal surfaces.

15 A further object of the invention is to provide an insulator having a rounded outer surface that will shed dust and other foreign matter.

A further object of the invention is to provide a device of the class named which shall be of 20 improved construction and operation.

Other objects and advantages will appear from the following description.

The invention is exemplified by the combination and arrangement of parts shown in the accompanying drawing and described in the following specification, and it is more particularly 25 pointed out in the appended claim.

In the drawing:

Fig. 1 is an elevation with parts in section showing one embodiment of the invention.

30 Fig. 2 is a fragmentary view showing a modification of a detail.

The insulator shown in Fig. 1 comprises two dielectric members 10 and 11 which may be made of suitable insulating material, such as porcelain. 35 The upper member 10 has a downwardly extending boss 12 having an upwardly opening recess in which a pin 13 is secured by cement 14. The upper end of the recess about the pin may be filled with asphalt or other suitable water-proofing material 15. The lower dielectric member 11 has an upwardly projecting boss 16 having a recess opening downwardly in which a pin 17 is secured by cement 18. The two bosses 12 and 40 16 are arranged end to end in axial alignment and are connected by a metallic sleeve 19 which may be provided with a web 20 separating the two portions of the sleeve to facilitate assembly of the bosses within the sleeve. The bosses are secured in the sleeve by cement 21. Each section of the sleeve is similar to the metal cap commonly used for suspension insulators except that instead of having an attaching member, the cover portions of the two caps are made in one so that 45 a double cap is provided having oppositely directed openings for receiving the bosses of the respective dielectric members. This arrangement brings the two bosses close together and provides a closely coupled double insulator unit.

50 Each of the dielectric members 10 and 11 is

provided with radially projected flanges, the flanges of the upper member being curved downwardly to provide an outer petticoat 22 which overlaps an upwardly projecting flange or baffle 23 on the lower dielectric member. A supplemental skirt 24 may be provided on the upper member so that the baffles 22, 23 and 24 cooperate to enclose the space about the sleeve 19 and form a labyrinthine passage connecting the interior of this space with the outer atmosphere. It will 10 thus be seen that the surface of the two porcelain members adjacent the sleeve 19 is always protected from contamination and provides a clean, dry leakage path of considerable extent between the two terminals 13 and 17. The lower 15 dielectric member 11 may be provided with additional skirts 25 and 26 to further increase the leakage and flashover path of the insulator or the two skirts 25 and 26, shown in Fig. 1, may be replaced by a single skirt 27 extending outwardly 20 at an inclination, as shown in Fig. 2.

It will be seen that the invention provides an insulator unit of relatively short string length having double dielectric strength due to the two dielectric members; the overall length being but 25 very little greater than that of the usual unit having a single dielectric member. In addition, the two dielectric members are provided with overlapping flanges which insure an extended surface protected at all times from contamination. 30 The insulator is also provided with an extended smooth outer surface which will be kept washed by rain so as to further increase the efficiency of the unit. The upper metal fitting, instead of being an extended cap, is a pin of limited extent 35 so that very little of the metallic surface is exposed.

I claim:

An insulator unit comprising a pair of dielectric members each having a boss thereon, a sleeve 40 connecting said bosses to secure said dielectric members together, a radially extending flange on each of said dielectric members, skirts on said flanges directed inwardly toward each other and enclosing the space about said sleeve and forming a labyrinthine passage connecting said space with the surrounding atmosphere, said bosses having outwardly opening recesses therein, said recesses being closed at their inner ends by the material of said bosses, and attachment pins 45 secured in said recesses for connecting said insulator unit to other units in a string, the inwardly directed position of the skirts providing clearance for close coupling of said units in the string so as to secure a minimum string length, while at 50 the same time the skirts enclose the sleeves of the various units in the string producing a string having a minimum exposure of its fittings.
